JAMES MATTISON DAVIS, OF DALLAS, TEXAS.

DISTANT-CONTROL-SWITCH SOCKET FOR ELECTRIC LIGHTS, &c.

1,303,464.

Specification of Letters Patent. Patented May 13, 1919.

Application filed June 8, 1917. Serial No. 173,612.

To all whom it may concern:

Be it known that I, JAMES M. DAVIS, a citizen of the United States, residing at Dallas, in the county of Dallas and State of Texas, have invented a new and useful Distant - Control - Switch Socket for Electric Lights, &c., of which the following is a specification.

This invention has reference to sockets for electric lights and other electric apparatus, and its object is to provide a socket structure which may be used in the ordinary manner of an electric light socket, or which may be controlled by a distant switch having circuit terminals introducible into or removable from the socket, at will.

The invention comprises a socket such as is customarily employed for electric lights and other purposes and through which current will flow to a translating device in the same manner as is customary in the electric sockets of either the key or the keyless type, and, in accordance with the invention, the socket is modified in such manner that the continuity of the circuit through the socket may be broken and the circuit diverted to a distant switch by which the current may be controlled to energize a translating device carried by or connected to the socket.

The invention will be best understood from a consideration of the following detailed description, taken in connection with the accompanying drawing forming part of this specification, with the understanding that while the drawing shows a practical form of the invention, the latter is not confined to any strict conformity with the showing of the drawing, but may be changed and modified, so long as such changes and modifications come within the scope of the appended claims.

In the drawings:—

Figure 1 is an elevation, with parts in section, showing a form of socket and a distant controlling switch with a plug connection whereby the switch may be coupled up to or uncoupled from the socket.

Fig. 2 is an elevation, partly in section, showing a somewhat different type of socket with the switch connecting plug inserted into the socket, the switch being omitted.

Referring to the drawings, there is shown a socket 1 which may, as indicated at Fig. 1, be of that type having a screw plug 2 as a permanent part of one end and a receptacle 3 as a permanent part of the other end. The

receptacle 3 may be considered as of the ordinary screw type and in the particular showing of Fig. 1 has an attachment plug 4 applied thereto, from which plug there leads a conducting cord 5, which may be assumed to lead to a translating device, not shown.

In Fig. 2 there is shown a socket 1^a with a receptacle 3 at one end and a cap 6 at the other end, through which cap there issues a cord 7 assumed to be connected to any suitable source of current. The socket 1 is indicated as of the keyless type and the socket 1^a is indicated as of the key type, the manipulating portion 8 of the key being indicated in Fig. 2. It will be understood that these two types of sockets may be taken as indicative of any type of socket or electric receptacle to which the invention may be adapted.

Ordinary sockets, like the sockets 1 or 1^a, and others of like character, have internal conductors whereby the circuit through them may be continuous, except that in the case of key or chain sockets suitable electric switching mechanism is provided within the socket.

In accordance with the invention one branch of the circuit within the socket is provided with terminals 9, 10, respectively, entering a cavity or chamber 11 formed in a body member 12 within the socket or receptacle, which body member is ordinarily made of porcelain. Within the chamber 11 are opposed spring fingers 13, 14, respectively, fast to respective terminals 9 and 10 and securely held thereby. In the particular arrangement shown each finger 13 and 14 is bent upon itself, with one leg fast to a terminal 9 or 10, as the case may be, and the other leg opposed and adjacent to the corresponding return leg of the other spring finger. The opposed legs are of a length to enter a recess 15 at one end of the chamber 11 and are protected from accidental access by the walls of the body member 12.

The free ends of the fingers 13 and 14 have a normal tendency to approach into firm contact and under such conditions complete the particular branch of the circuit, within the socket, in which said fingers are included. That end of the chamber 11 remote from the recess 15 is provided with a mouth 16 ordinarily opening through one side of the socket to the outside thereof.

There is also provided a plug 17 consisting of a tapered core member 18 of insulating material, and spring fingers 19 on opposite

sides of the core. The fingers 19 have a normal tendency to separate, for a short distance, from the core 18, so that when the plug is introduced into the chamber 11 through the mouth 16 thereof the fingers 19 engage the fingers 13 and 14 and are pressed toward each other until further movement is arrested by the tapered core member 18, and the fingers 13 and 14 are moved, in opposition to their normal tendency, until the ends within the recess 15 are separated out of electrical contact with each other. The plug 17 is carried by a manipulating member 20, which may be in the form of a sleeve of insulating material with a screw collar 21 at one end engaging a flange 22 on the plug 17 and clamping the latter in the manipulating member 20. Binding screws 23 are located on the plug in such position as to be within the manipulating member when the sleeve 21 is in position to clamp the flange 22 against the corresponding end of said manipulating member. The screws 23 are designed to secure the ends of conductors included in a conducting cord 24 which, at the end remote from the manipulating member 20, is suitably connected up to a switch 25 shown in Fig. 1 as of a familiar type of push-through switch.

30 Either socket shown in the drawings may be employed for feeding electric translating devices at any desired distance therefrom, as by the conducting cord 5 shown in Fig. 1, or may be employed to directly support an electric light bulb 26, as in Fig. 2. Such showing is deemed sufficient to indicate that the sockets may be used for any purpose for which electric sockets or receptacles are commonly used.

40 The improved socket is susceptible of use in the same manner as an ordinary electric socket, that is, it may be used to feed electric transmitting devices without control at the socket, as in the showing of Fig. 1, or 45 with control at the socket, where the latter is of the type containing a switch within the socket, as in Fig. 2.

It is often desirable, however, to be able to control the flow of current through the 50 socket from some distant point too far away from the socket to permit the use of a key switch or a chain switch. With the device of this invention, a distant controlled switch, such as the switch 25, may have its plug 17 introduced, through the side or other part of the socket, into the chamber 11 to separate the spring fingers 13 and 14 and bring them into good electric contact with the spring fingers 19, whereby the control switch is electrically interposed between the fingers 13 and 14 and is therefore included in the corresponding side of the circuit. If the switch 25 be open, no current will flow through the socket to the translating device controlled by the socket, but if the switch 25 be closed

then the circuit through the socket is completed. In this way a person quite distant from the socket may control the latter as easily as a person close to the socket can control the circuit through the customary switch 70 ordinarily in the socket. The invention has the advantage over wall or other fixed switches in that the switch 25 is readily portable to any position, since the conducting cord 24 may be as long as desired and is of 75 a flexible nature. Furthermore it is frequently desirable to be able to control an electric light or other translating device from a temporary location, in which case the switch 25 will answer the purpose. Nor 80 need the switch 25 be constantly coupled up in the circuit, because the plug 17 is readily separable from the socket at any time. The switch 25 when attached to the socket is in series therewith but on its disconnection 85 from the socket the latter is restored to the condition of an ordinary socket so far as its electrical connections are concerned.

What is claimed is:—

1. An electric socket or receptacle having 90 means for the inclusion of the socket in an electric circuit, means for the attachment of a translating device to the socket, interior circuit connections with accessible circuit terminals having a normal tendency to close 95 the circuit through the socket, a plug with circuit terminals introducible into the socket to engage the accessible circuit terminals therein and separate them to divert the circuit through the plug with the latter 100 in series with the socket or receptacle, flexible conductors connected to the plug, and a distant switch connected to the flexible conductors.

2. An electric socket or receptacle having 105 means for the inclusion of the socket in an electric circuit, means for the attachment of a translating device to the socket, interior circuit connections including spring fingers having a normal tendency to contact, said 110 socket being provided at one side with an opening through which the spring fingers are accessible from the outside of the socket, a plug with spring fingers constituting circuit terminals and introducible through the 115 opening in the socket into separating engagement with the spring fingers in said socket, a flexible conducting cord connected to the terminals of the plug, and a switch fast to the end of the cord remote from the 120 socket.

3. An electric socket or receptacle having 125 interior circuit connections, spring fingers within the socket and included in the circuit connections, said fingers having a normal tendency to engage and said socket having an opening at one side through which the spring fingers are accessible from the exterior of the socket, and a plug provided with adjacent spring fingers, and a tapered 130

- core member of insulating material between the spring fingers, said spring fingers having a normal tendency to move away from the core member and the spring fingers and
5 core member being adapted for introduction between the spring fingers in the socket to separate the latter and cause the spring fingers on the plug to move into engagement with the core member.
- 10 4. An electric socket or receptacle for receiving the terminals of a translating device and provided with through connections having normally engaged, separable circuit terminals, and an exterior switch means, circuit terminals separate therefrom, and flex-
- 15

ible connections between the last named circuit terminals and the switch means, whereby the said last named circuit terminals may be introduced into the socket for the control of the circuit within the socket 20 at will by the switch or the switch may be wholly removed without interference with the electric continuity of the socket.

In testimony that I claim the foregoing as my own, I have hereto affixed my signature in the presence of two witnesses.

JAMES MATTISON DAVIS.
